BRAKE ASSEMBLY

Robert R. Crookston, Houston, Tex., assignor, by
mesne assignments, to Standard Oil Develop-
ment Company, Elizabeth, N. J., a corporation
of Delaware

Application August 19, 1946, Serial No. 691,486

10 Claims. (Cl. 188—151)

1

The present invention is directed to a device adapted to control the speed of rotation of a body mounted for movement about a fixed axis. More particularly, the present invention is a device adapted to control the rate of rotation of a hoisting drum which is supporting a load by means of a line wound on the body of the drum.

For example, in the drilling of a borehole by the rotary drilling method, the drill stem employed when drilling deep holes is so long that the total weight of the drill stem is not allowed to rest on the drill bit and in such operations a part of the weight of the drill stem is taken by the travelling block which in turn is suspended from the crown block of the derrick by the hoisting line which has an end attached to the hoisting drum or draw works. In order to have an efficient operation, it is desirable that the load carried by the drill bit be relatively uniform. If insufficient weight is carried on the bit, it does not penetrate as rapidly as is desirable while if the weight carried by the bit is excessive the hole produced may be crooked or the drill stem may be twisted off.

It is an object of the present invention to produce an arrangement which allows the speed of rotation of a hoisting drum to be accurately controlled while producing a minimum amount of shock and irregularity of movement of the hoisting drum.

It is a further object of the present invention to produce a device which is capable of closely controlling the speed of rotation of a hoisting drum carrying a heavy load supported by a line and which is capable of terminating the rotating movement substantially instantaneously whenever desired by the operator.

It is a further object of the present invention to devise a means for controlling the speed of rotation of a hoisting drum to be controlled with little manual effort by an operator.

Other objects and advantages of the present invention may be seen from the following description taken in conjunction with the drawing in which

Fig. 1 is a front elevation with parts cut away showing an embodiment of the present invention;

Fig. 2 is a side elevation, with some parts cut away and some parts shown in section;

Fig. 3 is a view taken along line III—III of Fig. 1;

2

Fig. 4 is a view showing in detail the construction of a valve of the assembly of Fig. 1;

Fig. 5 is a view showing in detail the movable element of the valve shown in Fig. 4;

Fig. 6 is a view showing in detail the construction of another of the valves of the assembly of Fig. 1;

Fig. 7 is a flow diagram showing the conduits fluidly connecting the various parts of the apparatus illustrated in Fig. 1; and

Fig. 8 is a fragmentary view showing electrical means used for operating a portion of the apparatus.

The device of the present invention may be described briefly as involving a plurality of brake bands mounted on a frame supporting a hoisting drum with the brake bands arranged for limited arcuate movement and control means for tightening one band while the other is loose and for regulating the movement of the tight band and control means for simultaneously tightening all of the bands to stop completely the rotation of the hoisting drum.

In its more specific aspects, the device of the present invention involves two brake bands mounted on a frame supporting a hoisting drum and arranged for limited arcuate movement with the axis of the movement of the brake bands coinciding with the axis of rotation of the hoisting drum. Each brake band is mechanically connected to a piston slidably arranged in a cylinder and the cylinders, in turn, are secured to the frame and a conduit is arranged for fluidly connecting like ends of the cylinders whereby movement of a piston in one of the cylinders is possible only when the piston in the other cylinder moves in the opposite direction. In other words, it is a feature of the present invention that a pair of brake bands is mounted for arcuate movement on a frame with the brake bands connected to a fluid containing system whereby one of the brake bands can move through an arc only when the other brake band moves in the opposite direction and through the same arc. Means are arranged for contracting the brake bands in turn about the hoisting drum whereby a first brake band is locked to the hoisting drum and moves through its predetermined arc while a second brake band is released from the hoisting drum and moves in the opposite direction; when the first brake band

has moved through its predetermined arc, the second brake band is contracted to lock it to the hoisting drum and the first brake band is released, the second brake band is then moved in the same direction of rotation as did the first brake band when it was locked to the hoisting drum and simultaneously, the first brake band returns to its original position. When the second brake band has moved through its arc with the hoisting drum, the first brake band is locked to the hoisting drum, the second brake band is released from the hoisting drum and the cycle is repeated.

It is a further feature of the present invention that any time at the option of the operator both brake bands may be contracted thereby completely stopping the rotation of the hoisting drum. When it is desired to stop the rotation of the hoisting drum completely, both brakes may be contracted without altering the hydraulic system previously referred to and if subsequently the hoisting drum is to be released, the apparatus may be placed in operation for rotation of the hoisting drum at the same speed used prior to the complete stopping of the drum.

Turning now specifically to the drawing, the apparatus will first be described generally. A frame "A" has a drum assembly B mounted thereon for rotation about a fixed axis. The frame and drum assembly may be a conventional hoisting apparatus or draw works, commercially available. Mounted on drum assembly B are brake band assemblies C and C'. Corresponding portions of brake band assemblies C and C' are connected hydraulically with assembly D. Corresponding portions of brake band assemblies C and C' are also connected with system E; system E including parts shown within the dashed rectangle identified by numeral 10 on Figs. 1 and 7 and parts shown as the control panel designated by the numeral 6 in Fig. 7. The system E may be described as one adapted to operate through the medium of a compressible fluid maintained at superatmospheric pressure; this compressible fluid may, for example, be air, nitrogen, or fine gas, but for convenience hereafter the material will be referred to as compressed air.

A handbrake assembly F is mounted on frame A and is arranged for applying a braking force to the brake drum assembly B for emergency operation. It is to be noted that, in order to illustrate the invention more adequately, the Fig. 2 is shown with a rope or line 11 carried by drum assembly B whereas, in order to prevent confusion of such a showing with the various conduits on Fig. 1, the line 11 has been omitted from Fig. 1.

Drum assembly B is mounted on frame A for rotation about a fixed axis indicated by numeral 12 in Fig. 2. Drum assembly B defines cylindrical surfaces 13 and 13' adapted to cooperate with brake band assemblies C and C', respectively. Drum assembly B comprises a cylindrical surface 14 between the brake band assemblies arranged for receiving line 11 in the usual manner.

Brake band assemblies C and C' are exactly alike with the parts of assembly C identified by numerals, and corresponding parts of assembly C' identified with corresponding primed numerals.

By reference to Fig. 2, brake band assembly C will be seen to include arcuate band 15 and arcuate band 16 with ends of the band held together with adjustable clamp 17. A power unit comprising cylinder 18, piston 19 arranged to recip-

rocate therein, and piston rod 20 with one end attached to piston 19 and projecting through the piston rod end of cylinder 18, is mounted by trunnions 21 to plates 22 carried by arcuate member 15. The free end of piston rod 20 is fastened through pin 23 to link 24 which has its other end secured to arcuate member 15 by pin 25. Lever 24 is pierced to receive a pin 26 which serves to attach an end of link 27 to link 24. Link 27 is also attached through pin 28 to clevis 29 which, in turn, is secured to the end of arcuate member 16 through pin 30. Pin 28 also serves to attach clevis 29 and link 27 to link 31 which, in turn, is secured to arcuate member 15 through pin 32.

A cylinder 33, with its lower end secured to frame A, has a piston 34 slidably mounted therein. Piston rod 35 is attached to the piston 34 and projects through the piston rod end of the cylinder. Piston rod 35 is secured to a projection 36 of arcuate member 15 by a pin 37. It may be noted that the arrangement of cylinder 33 with piston 34 mechanically connected to arcuate member 15 serves as a hold-down for the brake band when force is applied by means of piston 19 and cylinder 18. If desired, instead of relying upon the piston 33 and piston rod 35 as a hold-down means, a transverse opening 38 is provided in projection 36 which serves to receive a suitable means, not shown, such as a link and pin, securing projection 36 to frame A.

A valve member 39 is mounted on the piston rod end of cylinder 33 and a means 40 for operating valve member 39 is mounted on piston rod 35.

The parts making up auxiliary hand brake assembly F are shown in Figs. 1, 2, and 3. This assembly includes parallel shafts 41 and 42; shaft 41 is journaled to frame A through journals 43 and 44 and shaft 42 is journaled to the frame by journals 45 and 46. A hand lever 9 is mounted on the outboard end of shaft 41. A pair of crank arms 47 is mounted on shaft 41 for rotation therewith and a pair of crank arms 48 is mounted on shaft 42 for rotation therewith; the ends of these pairs of crank arms are connected together through link 8. A second pair of crank arms 49 is also mounted on shaft 42 for rotation therewith with the aforesaid crank arms linked through members 50 and 51 and bolt 52 to equalizer 53. It will be seen that the lower surface of the equalizer 53 is slidably arranged on frame A.

One end of the equalizer 53 is connected through chain 55 to arcuate member 16 of brake band assembly C, while the other end of the equalizer member is connected through chain 55' to arcuate member 16' of brake band assembly C'. It is to be noted that with the lever arm in the position shown in the drawings, the chains 55 and 55' are slack, thereby allowing the brake band assemblies C and C' to be operated by compressed air without bringing the hand operated brake into play; it will be obvious that movement of the hand lever 9, to rotate shaft 41 in a clockwise direction, as viewed in Fig. 2, will first take up the slack in chains 55 and 55' and then tighten the brake band assemblies C and C' against surfaces 13 and 13', respectively, of the hoisting drum.

The hydraulic system D fluidly connecting the cylinders 33 and 33' of assemblies C and C' includes a conduit 60 connected to the piston rod end of cylinder 33 and a conduit 60' fluidly connected to the piston rod end of cylinder 33'. The conduits 60 and 60' are fluidly connected

with a branch line 61 containing check valves 62 and 63 and a conduit 64 containing check valves 65 and 66. That portion of conduit 61 between check valves 62 and 63, and that portion of conduit 64 between check valves 65 and 66 are connected with three branch lines 67, each controlled with adjustable needle valve 68. The hydraulic system fluidly connecting brake band assemblies B and B' also includes a conduit 69 fluidly connecting the head end of cylinder 33 with the head end of cylinder 33'.

The arrangement of the hydraulic system D with check valves 62, 63, 65, and 66 is for the purpose of insuring that the liquid passing from conduit 60 to 60' and from conduit 60' to 60 will always flow in the same direction through needle valves 68. Now, if it be assumed that the fluid is to pass from the piston rod end of cylinder 33 to cylinder 33', the fluid passes through conduit 60, check valve 62, upwardly through one or more of the branch lines 67, in parallel through one or more of adjustable needle valves 68, into conduit 64, through valve 66, and into conduit 60' and into the piston rod end of cylinder 33'. If it be assumed that fluid is to pass from the piston rod end of cylinder 33' to the piston rod end of cylinder 33, liquid passes through conduit 60', through valve 63 in conduit 61, and then through one or more of the branch lines 67 controlled by needle valves 68; the fluid then passes through conduit 64 and check valve 65 to conduit 60 and thence into the piston rod end of cylinder 33.

It is not necessary that the line 69 and the head ends of cylinders 33 and 33' contain a liquid, but in order to provide for smoothness of operation, liquid is also placed in these parts; it will be obvious that, as piston 34 in cylinder 33 moves upwardly, and the liquid from the piston rod end of cylinder 33 passes to the piston rod end of cylinder 33', an equal amount of fluid is displaced from the head end of cylinder 33' through conduit 69 into the head end of cylinder 33 and similarly, when the piston in cylinder 33' moves upwardly and displaces fluid from the piston rod end of cylinder 33', an equal amount of liquid is displaced from the head end of cylinder 33.

The assembly E for supplying and controlling the flow of compressed air into cylinders 18 and 18' of brake band assemblies C and C' includes a control panel 6 which is fluidly connected to a source of compressed air through an inlet 71 hereinafter designated as the main air line. Mounted on the control panel 6 is member 72 which may be described as a double valve mechanism having a single control member 73. Control member 73 may be in a neutral position with both of the valve members inoperative, or may be moved to a first position, for example upward, to operate a first valve member indicated in the drawing as 74, or it may be moved from the neutral position to a second position, for example downward, to operate the second valve element indicated in the drawing as 75. Branch line 76 connects the inlets of valve elements 74 and 75 to main air line 71; the outlet of valve element 74 is connected to conduit 77, while the outlet of valve element 75 is connected to conduit 78.

It will be understood that movement of control member 73 from neutral to the first position allows fluid communication between main air line 71 through conduit 76 to conduit 77, while movement of control member 73 from the neu-

tral to the second position allows fluid communication through main air line 71 and branch line 76 to conduit 78. The valve member 72 is of the conventional type, having exhaust ports, not shown, which allow air to be bled from conduits 77 and 78 when the control member 73 is returned to neutral position.

10 A conduit 80 connects to the main air line 71 and the flow of air through this conduit is controlled by valve 79 mounted on control panel 6. It may be mentioned that valve 79 is preferably of the type adjusted with a hand wheel so that the constriction of flow through the valve may be adjusted by the operator and the valve left at this setting over substantial intervals of time.

20 A unit designated as double check valve 81 consists of a casing 82 having a member 83 slidably arranged therein with inlet ports 84 and 85 at the ends thereof and outlet port 86 at its center. The double check valve 81 is arranged so that fluid may pass from inlet port 84 to outlet port 86 when member 83 is adjacent inlet port 85 and so that fluid may pass from inlet port 85 to outlet port 86 when the movable member is adjacent inlet port 84. Inlet port 84 is fluidly connected to conduit 78 and inlet port 85 is fluidly connected to conduit 80. Outlet port 86 is connected to conduit 87.

30 Arranged in main air line 71 is a diaphragm valve 88 which is arranged to control the flow of air through main air line 71. The operation of the diaphragm valve controlled by the pressure of fluid in diaphragm member 90 which is connected by conduit 89 to branch line 78. The outlet of valve 88 is connected to conduit 91.

40 Also mounted on the control panel 6 is valve 92 having its inlet connected to the main air line through conduit 93 and its outlet connected to conduit 94. The valve 92 may be of a commercially available type arranged normally to be maintained in a closed position and to be opened only when the operator manually contacts a control means, as an operating control member 95.

45 Compressed air is supplied to cylinders 18 and 18' of brake band assemblies C and C' through valve members 100 and 100', respectively. Valve members 100 and 100' are identical in construction.

50 The construction of valve member 100 is shown in detail in Figs. 4 and 5. Member 100' will not be described in detail. It will be understood that although the several parts of valve member 100' are not shown in detail, this member has exactly 55 the same construction as valve member 100 with the like parts identified with corresponding primed numerals. Housing 101 has a member 102 slidably arranged therein. Slidable member 102 defines a passage 103 which may be described as being generally in the shape of a capital U. The base of the U-shaped fluid passage 103 is in fluid communication with an inlet 104 in housing 101, while the upper portions of the U-shaped passage are fluidly connected either to outlet 105 60 or 106 in the housing 101, depending upon the position of member 102. If slidable member 102 is in the position, shown in the drawing herein-after referred to as the first position, air passes from inlet port 104 through passage 103 to outlet

65 port 106; if the slidable member is at the other end of housing 102, herein-after referred to as the second position, air passes from inlet port 104 through passage 103 to outlet port 105. Slidable member 102 is also provided with a passage 107 70 at one end thereof and a second passage 108 at

the other end thereof; these passages will herein-after be referred to as exhaust passages. When member 102 is in its first position, exhaust passage 107 allows communication between outlet port 105 and outlet port 109 of the housing and, similarly, when member 102 is in the second position, exhaust passage 108 allows fluid communication between outlet ports 106 and outlet port 1.

The slidable member 102 is connected to rod 111 passing through a suitable fluid-tight gland, not shown, of housing 102, and member 102' is connected to rod 111' similarly passing through a fluid-tight gland, not shown, in housing 101'. The adjacent ends of rods 111 and 111' are connected to opposite sides of diaphragm member 112. The end surfaces of member 102 cooperate with housing 101 to form a substantially fluid-tight seal and access to the space at the head-end of housing 101 is provided by inlet port 110. Similarly, access to the head-end of housing 101' is provided by inlet port 110'.

The entire flow circuit of the compressed air system will now be described. The circuit is shown in Fig. 7. A relay valve 120 has its inlet connected to main air line 121 and its outlets connected by branch lines 122 and 122' to inlets 104 and 104' of valve members 100 and 100'. Relay valve 120 is of a conventional type, with the operation of the relay controlled by the pressure in conduit 87 which fluidly connects the relay valve with the double check valve 81. An exhaust port 123 is provided in the relay valve for exhausting air from lines 122 and 122' to the atmosphere when the relay is closed.

A second relay valve 124 has its inlet fluidly connected to main air line 125 and has its outlet lines connected through conduits 126 and 126', respectively, the ports 109 and 109' of valve members 100 and 100', respectively, to allow the brakes to be released under power; at all other times the relay valve functions as a quick release valve in emitting air from the head ends of cylinders 103 and 100'. The operation of relay valve 124 is controlled by the air pressure in conduit 77, which is connected to valve assembly 72. Relay valve 124 is provided with an outlet 127 for exhausting lines 126 and 126' to the atmosphere when the relay valve is closed.

It will be understood that the construction and use of relay valves are well known to the art. The purpose of a relay valve is to relay or repeat the operation of a controlling valve or device. An increase of the control pressure actuates the relay valve to produce the same or a proportional pressure in an air cylinder; likewise, a reduction of the control pressure results in a similar or proportional reduction of cylinder pressure. With a relay valve in the pipe between the controlling valve and an air cylinder and connected to a large source of air supply, the controlling valve serves to pilot the large capacity flow to and from the air cylinder. The use of a relay valve thus provides that a small capacity controlling valve may be used to control the operation of a large capacity air cylinder.

In valve housing 100 outlet port 105 is fluidly connected to the head end of cylinder 18 in brake band assembly C through conduit 128, and outlet port 106 is fluidly connected to the rod end of cylinder 18 through conduit 129. Similarly, the head end of cylinder 18' in brake band assembly C' is connected to outlet 105' of assembly 100' through conduit 128' and the rod end of cylinder 18' is connected to outlet 106' through conduit 129'.

In assembly 100' the inlet 110' is connected through conduit 130 to double check valve 131. The double check valve 131 is similar in construction to double check valve 81, previously described, and, accordingly, will not be described in detail, since this would be merely a repetition of the description of double check valve 81. One of the inlet ports of double check valve 131 is connected through conduit 132 to cam-operated valve 39, which is connected to main air line 134. The other inlet of double check valve 131 is connected through line 94 to valve 92, heretofore described.

In assembly 100, inlet 110 is connected through conduit 130' to cam-operated valve 39', which is connected to main air line 134'.

In order for the brake assemblies C and C' to maintain control of hoisting drum assembly B at all times, it is desirable when one brake band assembly is being released and the other being engaged for that assembly being engaged to act more quickly than the assembly being released. To insure such an operation a check valve 135 is arranged in each of lines 128, 129 and 128' and 129'. An enlarged view of one of the check valves 135 is shown in Fig. 6. It will be seen that the check valve consists of a valve body 136 defining an air passage 137 and arranged in the air passage is a member 138 attached with a hinge 139 to the valve body. Member 138 is pierced by a plurality of openings 140. For convenience, an arrow is placed adjacent each of check valves 135 in Fig. 6 to indicate the direction in which the flow of fluid causes member 138 to be raised to clear the passage to allow free flow of air through the valve. When the air flows through valve 135 in the direction opposite from that in which the arrow is pointing, the air is forced to pass through the relatively small openings 140.

The arrangement of valves 135 in each of lines 128, 129, and 128' and 129' insures that the brake band assembly being tightened on the hoisting assembly operates more quickly than that which is being released. If it be assumed, for example, that brake band assembly C is being tightened while assembly C' is being released, the air flows freely through valve 135 in line 129 to the piston rod end of cylinder 18 and flows freely through line 128 and valve 135 from the head end of cylinder 18; in other words, the air flows freely into the inlet and from exhaust of the cylinder which is to apply the brake band. At the same time the flow of air into the head end of cylinder 18' is restricted by the necessity of the air passing through the ports 140 of valve 135 in line 128' and similarly the exhaust of air from the piston rod end of cylinder 18' is restricted by being forced to flow through the openings 140 of the valve 135 in line 129'. When assembly C' is being engaged to the brake drum and assembly C disengaged, the same conditions are established, that is to say, the flow of fluid into and from cylinder 18' to engage brake assembly C' is rapid while the flow of fluid into and from cylinder 18 to release the brake assembly C is restricted.

It will be evident that the mechanism for engaging and disengaging brake band assemblies C and C' to drum assembly B may be motivated by arrangements other than the use of air pressure as shown in Figs. 1 to 7, inclusive. A mechanism for operating the valve assemblies 100 and 100' employing electricity as the means of controlling these valves is shown in Fig. 8.

In Fig. 8 the lines 122, 126, 128, 129, and 122', 126', 128', and 129' are connected in exactly the same manner as in the circuit diagram of Figs. 1 and 7. The brake band assemblies C and C' (not shown in Fig. 8 but identical with the showing in the embodiment illustrated in Figs. 1 to 7) also have mounted thereon the switch activating mechanisms 40 and 40' corresponding exactly to that shown in Figs. 1, 2, and 7. Similarly, line 71 represents a main air line in the same way as in preceding Figs. 1 and 7. The means for operating valves 100 and 100', however, differs from that of the previously described embodiment employing an electrical circuit rather than a fluid means.

In Fig. 8 main air line 71 is connected to inlet port 110 of valve mechanism 100 by means of a branch line 150 controlled by valve 141. Similarly, main air line 71 is connected to inlet port 110' of valve 100' by branch line 150' controlled by valve 141'. Valves 141 and 141' are operated by electricity and may be any of the conventional types known to the art. Inasmuch as such valves are known, the details of the construction of valves 141 and 141' will not be described. An electrical conductor 142 is shown attached to valve 141 through branch line 143 and to valve 141' through branch line 144; a plus sign indicates that conductor 142 is connected to a positive source of electricity. A conductor 145' having a switch 146' arranged therein is connected to valve 141; a minus sign indicates that conductor 145' is connected to a negative source of electricity. Conductor 145 containing a switch 146 is similarly indicated as connecting valve 141' to a negative source of electricity.

Switch 146 cooperates with element 40 in a manner analogous to that which valve 39 cooperates with element 40 in the embodiment of Figs. 1 to 7. Similarly, switch 146' cooperates with element 40' in a manner analogous to that of valve 39' and element 40' of the embodiment of Figs. 1 to 7. While switches 146 and 146' are shown diagrammatically only, it will be understood that it is usually desirable to employ the switches known as limit switches for this purpose; such a switch is positively acting in that once it is closed a substantial movement of element 40 is necessary before the switch will open and mere vibration of the assembly will not open the switch. When element 40 contacts switch 146 and closes it, current is allowed to pass to valve 141' and opens the valve whereby air from the main air line flows through branch line 150' to inlet port 110' of valve 100' and operates the valve in the same manner as air passing through line 130 to inlet port 110' of the embodiment of Figs. 1 to 7, and when element 40 moves out of contact with switch 146 valve 141' closes as does valve 39 when element 40 moves out of contact with it. Similarly, when element 40' closes switch 146' the current passes to valve 141 and opens it to allow air to flow from main air line 71 through branch line 150 to inlet port 110' of valve 100' and activates it in the same way. When element 40' moves out of contact with switch 146', valve 141 is closed and prevents communication between main air line 71 and branch line 150. It will be understood that in the embodiment illustrated generally any suitable type of electrically operated valves, with a suitable type of electricity, either alternating or direct current, may be employed as desired.

The operation of the assembly of the present invention in what may be termed the normal op-

eration of the device, that is, when paying out line under load will now be described. When the assembly operates in this manner the brake band assemblies C and C' oscillate in opposite directions, that is to say, when assembly C moves in a counterclockwise direction, as in view Fig. 2, brake band assembly C' moves in a clockwise direction, and when the direction of movement of assembly C is reversed so that it moves in a clockwise direction, the assembly C' then moves in a counterclockwise direction. This motion of the brake band assemblies may be described as a walking motion.

The relationship of the various parts with the normal operation described in the preceding paragraph will now be examined in detail. With the parts in the relative positions indicated in Fig. 1, drum assembly B is moving in the counterclockwise direction, as viewed in Fig. 2, under the load supported by cable 11, and brake band assembly C is engaged with the brake drum 13 and moving with it, while assembly C' is loose on brake drum 13' and moving in the opposite direction from brake band assembly C. Control member 73 is in its neutral position and valve 79, which may be of the pressure regulating type, is in the open position, these control valves having been given these settings by the operator for initiating normal operation. Pressure regulating valve 79 is so set that the pressure in line 80 is lower than the pressure in line 78 when line 78 is fluidly connected with main air line 71 through valve 72 and line 76. With control member 73 and valve 79 in the aforementioned positions, air flows from main line 71 through branch line 80, valve 79, double check valve 81 and line 87 to relay valve 120. Air also flows through double check valve 81 into line 87 because slidable element 83 is forced to the left extremity of double check valve 81 by reason of the pressure in line 80 being greater than the air pressure in line 78, line 78 having previously been bled by valve 72, which is of the bleeder type, when control member 73 was placed in the neutral position. Relay valve 120 is held open by means of the pressure exerted by air flowing in line 87. With relay valve 120 open air flows from main air line 121 to branch lines 122 and 122', thence to valve assembly 100 and 100', respectively. Slidable element 102 is located in valve assembly 100 adjacent the end defining port 110 and consequently the air in line 122 enters valve assembly 100 through port 104, fluid passage 103, port 106, and through line 129 into the piston rod end of cylinder 18; this causes air pressure to be exerted against the piston rod end of piston 19 and thus maintaining brake band assembly C tight on drum 13. While air is flowing through line 122, it is also flowing through line 122', entering valve assembly 100' through port 104'. Slidable element 102' is located in valve assembly 100' opposite the end which defines port 110', inasmuch as slidable elements 102 and 102' are connected together by means of rods 111 and 111' and diaphragm member 112. With member 102' in the aforementioned position, air entering valve assembly 100' through lines 122' and port 104' flows through passage 103' and port 106' into line 128' and into the head end of cylinder 18'. This causes air pressure to be exerted against the head end of piston 19' thus maintaining brake band assembly C' loose on brake drum 13'. While brake band assembly C is thus engaged and brake band assembly C' is disengaged, piston 34 mechanically connected to brake band assembly C is

moving upwardly while piston 34' mechanically connected to brake band assembly C is moving downwardly. The upward motion of piston 34 is produced by the pull of cable 11 on brake drum assembly B causing rotation thereof. Inasmuch as brake band assembly C is engaged with brake drum assembly B at brake drum 13, brake band assembly C is also moving arcuately thus causing piston 34 to move upwardly in cylinder 33. As previously pointed out, cylinders 33 and 33' contain fluid and the portion of cylinder 33 above piston 34 is fluidly connected with the portion of cylinder 33' above piston 34' by means of lines 60, 64, 67, and 60'. The portion of cylinder 33 below piston 34 is fluidly connected with the portion of cylinder 33' below piston 34'. Line 61 also fluidly connects lines 60 and 60'. Line 64 contains check valves 65 and 66, while line 61 contains check valves 62 and 63, the aforementioned check valves permitting unidirectional flow in the lines in which they are located. Lines 61 and 64 are fluidly connected by means of one or more of branch lines 67 containing adjustable needle valve 68. As piston 34 moves upwardly, the fluid contained in the upper portion of cylinder 33 flows through line 60, check valve 65, line 64, line 67, controlled by needle valve 68, line 61, check valve 63, and line 60' into the upper portion of cylinder 33' forcing piston 34' downwardly therein. Since brake assembly C' is mechanically connected to piston 34', brake assembly C' is also caused to move arcuately to follow piston 34'. As brake band assembly C' reaches the end of its downward stroke, member 40' contacts valve 39', thereby opening valve 39' momentarily which, in turn, allows compressed air to flow from main line 134', through valve 39' and line 130' and to enter the end of assembly 100 which pushes movable element 102 away from inlet 110; simultaneously element 102' moves toward inlet 110' in assembly 100'. Upon this movement of element 102 compressed air in line 122 flows into valve element 100 through port 104, through passage 103, port 105, and line 128 into the head end of cylinder 18 thereby driving piston 19 toward the rod end of cylinder 18 and releasing brake band assembly C from brake drum 13. Conversely, on movement of element 102' toward inlet 110' in valve element 100', the air in line 122' flows into valve element 100' through port 104' into passage 103' through port 105' and line 129' into the piston rod end of cylinder 18' thereby driving piston 19' toward the head end of cylinder 18' and tightening brake band assembly C' on brake drum 13'. Tightened brake band assembly C' rotates with brake drum assembly B thereby causing piston 34' to move upwardly and simultaneously piston 34 is moving downwardly while brake band assembly C, mechanically connected to piston 34, is moving arcuately in the opposite direction from assembly C'. As brake band assembly C rotates with drum assembly B, the rotation of drum assembly B being produced by the pull of cable 11, piston 34', being mechanically connected to brake band assembly C', moves upwardly toward the piston rod end of cylinder 33'. While piston 34' is moving upwardly toward the piston rod end of cylinder 33', piston 34 is moving downwardly toward the head end of cylinder 33, the downward movement of piston 34 being caused by the flow of fluid from cylinder 33' through fluidly connecting conduits 60', 64, 67, 61, and 60 into piston 33. Inasmuch as brake band assembly C is mechanically connected to piston 34, it is caused to move arcuately in cooperation with piston 34. The

movement of brake band assembly C in due course brings member 40 into contact with valve 39 and opens this valve momentarily. The opening of valve 39 causes air to flow in line 130 which in turn causes movable element 102' in assembly 100' to move away from inlet end 110' and simultaneously causes movable element 102 in assembly 100 to move toward inlet end 110; this change in the valve setting admits air to the piston rod end of cylinder 18 and to the head end of cylinder 18', as hereinbefore described, thereby tightening brake band assembly C and releasing brake band assembly C', thus allowing the cycle heretofore described to be repeated.

The manipulation of valve members by an operator in order to control the movement of the hoisting drum will now be described. If it is desired to hold the drum stationary, this may be done by moving control member 73 to operate valve mechanism 75 which allows air to flow from main air line 71 and line 76 into lines 78 and 89, the pressure in lines 78 and 89 being equal to the pressure in main air line 71. The admission of main line air pressure to lines 89 and 78 simultaneously actuates diaphragm 90 to open valve 88 and forces slidable element 83 to the right extremity of double check valve assembly 81 to permit air to flow from line 78 through valve assembly 81 into line 87. The opening of valve 88 permits main line air pressure to enter line 91 and to spread diaphragm member 112 which, in turn, moves element 102 in assembly 100 toward the inlet end 110 and element 102' in assembly 100' toward inlet end 110'. The air admitted to line 87 through double check valve assembly 81 actuates relay 120, thereby permitting air from main air line 121 access through lines 122 and 122' to inlets 104 and 104' of assemblies 100 and 100', respectively. The expansion of diaphragm element 112 together with the admission of air to assemblies 100 and 100' allows air to pass through branch line 122, passage 103, and line 129 to the piston rod end of cylinder 18, and simultaneously allows air to pass through conduit 122', passage 103', and conduit 129' to the piston rod end of cylinder 18'; this tightens brake band assemblies C and C' simultaneously and prevents any rotation of drum B. The manipulative steps for bringing the assembly from rest to normal rotation under load are as follows. Valve 79 is opened and valve mechanism 75 may then be closed by the movement of control member 73 to neutral position. These steps allow air to bleed from lines 78 through valve 72 and the double check valve 81 to respond to pressure in line 80, with air passing from main air line 71 through line 80 and valve 79, double check valve 81 and conduit 87 to relay 120. The movement of control member 73 to neutral position allows diaphragm valve 88 to close with the pressure in line 91 bleeding off through outlet 88'. To assure that the valve elements 102 and 102' are in proper position, it is desirable then to move these elements into a known position; this could be done by the operator going from his control board and operating manually either valve 39 or valve 39', but for convenience valve 92, connected in parallel with valve 39, is arranged at the control panel and operation of this valve allows air to pass from main air line 71 to double check valve 131. The air pressure in line 94 controls the position of the double check valve 131 and allows air to flow through conduit 130 and to inlet 110', moving element 102' away from inlet 110' which, in turn, causes movement of element 102 toward inlet 110.

In other words, operation of valve 92 positions the movable parts of elements 100 and 100' so that air flows into the rod end of cylinder 18 and tightens brake band assembly C, while air is exhausted from the rod end of cylinder 18' of brake band assembly C', thereby releasing this assembly. The manipulation of valve 92 is the last manipulative step in the starting operation and the assembly then continually pays out line, or walks at a speed which is controlled by the rate liquid flows through one or more valves 68.

If it is desired to release both brake bands simultaneously, as when running a drill stem into the borehole, this may be done by moving control member 73 to operate valve mechanism 72. It is desirable to release both brakes only after both of the brakes have been applied, that is to say, after diaphragm member 112 has been expanded to position member 102 with its end adjacent inlet 110 and member 102' with its end adjacent inlet 110'; the elements 102 and 102' being in this position, the opening of valve 72 allows air from the main air line 71 to flow through conduits 76 and 77 to operate relay 124 which, in turn, allows air to pass from main air line 125 through relay 124 and to branch lines 126 and 126' which are connected to housings 101 and 101' at ports 109 and 109', respectively, and the air then passes through exhaust passages 107 and 107', respectively, conduits 128 and 128', respectively, and to the head ends of cylinders 18 and 18', respectively.

From the above description it will be seen that the device of the present invention allows the rotation of a hoisting drum, when paying out line under load, to be accurately and easily controlled. It will also be seen that the assembly allows the rotation of the drum to be stopped completely at any time at the option of the operator and also allows the brake band assembly to be completely disengaged from the hoisting drum at any time at the option of the operator. It will also be seen that in the event of an emergency when the power supply fails, the brake assembly may be operated manually to engage the brake bands frictionally with the brake bands in the conventional manner.

While I have disclosed specific embodiments illustrating the device of the present invention, it will be obvious to the workman skilled in the art that various changes in the shape, size and proportions of the several parts of the apparatus may be made without departing from the scope of the invention and it is my intention to embrace such changes by the hereto appended claims.

I claim:

1. Apparatus adapted to apply a restraining force to a hoisting drum mounted on a frame for rotation about a fixed axis comprising, in combination, a first brake band adapted to cooperate with the hoisting drum to apply braking force thereto, a first power means mounted on a first brake band and adapted to engage releasably the first brake band with the drum, a second brake band mounted for engagement with a surface of the hoisting drum, a second power means carried by the second brake band and adapted to engage releasably the second brake band with the surface of the drum and control means arranged to operate the first and second power means in sequence.

2. An apparatus in accordance with claim 1 in which the control means is arranged selectively to operate the first and second power means in sequence and simultaneously.

3. An apparatus adapted to apply a restraining force to a hoisting drum mounted on a frame for rotation about a fixed axis comprising, in combination, a first brake band mounted on the frame for limited arcuate movement about an axis coinciding with the axis of the hoisting drum, a second brake band mounted on the frame for limited arcuate movement about an axis coinciding with the hoisting drum, a first power means carried by the first brake band arranged to engage releasably the first brake band with the hoisting drum, a second power means carried by the second brake band adapted to engage releasably the second brake band with the hoisting drum and control means arranged selectively to operate the first and second power means in sequence and simultaneously.

4. An assembly including a frame, a hoisting drum mounted on the frame for rotation about a fixed axis and defining at least two cylindrical surfaces having an axis coinciding with the axis of rotation and adapted for cooperation with brake bands, a first brake band mounted on the frame for limited angular movement about the axis of rotation of said drum with respect to the frame and adapted to cooperate with one of said cylindrical surfaces, a second brake band mounted on the frame for limited angular movement about the axis of rotation of said drum and adapted to cooperate with the second cylindrical surface, means mounted on the first band arranged to tighten the band to prevent relative movement between the band and the drum, means mounted on the second band adapted to tighten the second band and prevent relative movement between the second band and the drum, a first cylinder mounted on the frame adjacent the first band, a first piston slidably mounted in said cylinder, means mechanically linking said first piston with the brake band including a first piston rod mechanically connected to said piston and extending through an end of the cylinder, a second piston mounted on the frame adjacent the second band, a second piston arranged for reciprocation in said second cylinder, means including a second piston rod connected to the second piston and extending through an end of the second cylinder mechanically connecting the second piston with the second band, a conduit including an adjustable orifice fluidly connecting the piston rod end of the first cylinder with the piston rod end of the second cylinder, means arranged to contract the first band to prevent relative movement between said band and the drum and to release the second band to allow relative movement between the band and the drum when the first band reaches a predetermined position and means arranged to contract the second band to prevent relative movement between the second band of the drum and to release the first band to allow relative movement between the first band and the drum when the second band reaches a predetermined position.

5. A device adapted for relating the speed of rotation of a body to which a rotational force is applied, said body being mounted on a frame upon rotation about a fixed axis comprising, in combination, a first brake band mounted on the frame and arcuate movement thereof a predetermined distance about the axis of rotation of the body and adapted to engage with a cylindrical surface defined by the body, a second brake band mounted on the frame and arranged for a limited arcuate movement about the axis of rotation of said body, a first cylinder mounted on the frame adjacent the first brake band, a first piston mounted

for reciprocation in the cylinder, means including a first piston rod connected to the piston and extending through one end of the cylinder mechanically connecting the piston with the first brake band, a second cylinder mounted on the frame adjacent the second brake band, a second piston arranged for reciprocating in the second cylinder, means including a second piston rod connected to the second piston and extending through one end of the second cylinder mechanically connecting the second piston with the second band, a conduit including an adjustable valve fluidly connecting the piston rod end of the first cylinder with the piston rod end of the second cylinder, a first releasable means mounted on the first brake band arranged for tightening the first brake band to prevent relative movement between the band and the drum, a second releasable means mounted on the second band arranged to tighten the second band to prevent relative movement between the second band and the drum, means including a valve mechanism mounted on the first band and arranged to be activated when the first band reaches a predetermined position with respect to the frame for activating the band tightening mechanism mounted on the first band, and for releasing the band tightening mechanism mounted on the second band and means including a valve mounted on a second band for activation when the second band reaches a predetermined position with respect to the frame for activating the second band tightening mechanism and releasing the first band tightening mechanism.

6. A device adapted to control the operation of brake bands for controlling the rate of rotation of a hoisting drum comprising, in combination, a first cylinder, a first piston arranged for reciprocating in the first cylinder, a first piston rod secured to said first piston and extending through one end of the cylinder, said piston rod being adapted for connecting with a brake band for contracting said band, a second cylinder, a second piston arranged for reciprocation in the second cylinder, a second piston rod connected to the second piston and extending through an end of the second cylinder and adapted to be attached to a second brake band for contracting the band, a first and second master valve, said master valves each being provided with a slideable piston and the pistons of the two master valves mechanically connected, an inlet line adapted to be connected to a supply of compressible fluid at superatmospheric pressure connected to each of the master valves, a conduit fluidly connecting the first master valve with the piston rod end of the first cylinder for supplying compressible fluid to the piston rod end of the cylinder when the piston of the first master valve is in its first position, and for exhausting air when said piston of the first master valve is in its second position and a second conduit connecting the head end of the first cylinder with the first master valve for connecting said head end with the compressible fluid at superatmospheric pressure when the piston in the first master valve is in its second position and exhausting fluid from the head end of the first cylinder when the piston of the master valve is in its first position, a third conduit fluidly connecting the second master valve with the piston rod end of the second cylinder for supplying compressible fluid at superatmospheric pressure to said piston rod end when the piston of the second master valve is in its first position and for exhausting compressible fluid when the piston of the second master valve is in a second position.

a fourth conduit fluidly connecting the second master valve with the head end of the second cylinder for supplying compressible fluid thereto when the piston of the second master valve is in its second position and for exhausting fluid therefrom when said piston of the master valve is in its first position, and means activated by movement of one brake band for moving the piston of the first and second master valves from their second to their first and their first to their second positions, respectively, and means arranged to be activated by the other brake band for moving the pistons of the first and second master valves from their first to second and second to first positions, respectively.

7. A device in accordance with claim 6 in which the means mechanically linking the piston of the first and second master valves is arranged for forcing both pistons to their first position.

20 8. A hoisting drum assembly comprising, in combination, a frame, a hoisting drum mounted on the frame for rotation about a fixed axis and defining a first surface and a second surface symmetrical with said axis, a first brake assembly mounted on the frame for movement through a predetermined arc having an axis coinciding with the axis of the drum and mechanically linked to a first element and adapted to assume a first and a second position, a second brake assembly mounted on the frame for movement through a predetermined arc having an axis and magnitude corresponding to the arc of movement of the first brake assembly and mechanically linked to a second element and adapted to assume a first and a second position, a first element carried by the first brake assembly and defining a surface adapted to engage frictionally with the first surface of the drum, a second element carried by the second brake assembly and defining a surface adapted to engage frictionally with the second surface of the drum, means fluidly connecting the first and second brake assemblies and arranged to cause movement of the brake assemblies in opposite directions, a means mounted on the first 45 brake assembly arranged to engage the first element with the first surface of the brake drum and to disengage the second element from the second surface of the brake drum when the first brake assembly is in its first position and means 50 carried by the second brake assembly adapted to engage the second element with the second surface of the brake drum and disengage the first element from the first surface of the brake drum when the second brake assembly is in its first 55 position.

9. An apparatus adapted to apply a restraining force to a hoisting drum mounted on a frame for rotation about a fixed axis comprising, in combination, a first brake band mounted on the frame 60 for limited arcuate movement about an axis coinciding with that of the drum, a second brake band mounted on the frame for limited arcuate movement about an axis coinciding with that of the drum and control means arranged selectively to engage and disengage said brake bands in sequence and to engage and disengage said brake bands simultaneously.

10. A feed-off means for a hoisting drum mounted on a frame for rotation about a fixed axis comprising, in combination, a first braking means mounted for arcuate movement about an axis coinciding with that of the drum, a first piston and cylinder assembly secured to said first braking means and to the frame arranged for 70 relative longitudinal movement between the pis-

ton and cylinder upon arcuate movement of said first braking means, a second braking means mounted for arcuate movement about an axis coinciding with that of the drum, a second piston and cylinder assembly secured to said second braking means and to the frame arranged for relative longitudinal movement between the piston and cylinder upon arcuate movement of said second braking means and control means arranged selectively to engage and disengage said first and second braking means mechanically with said hoisting drum.
